UNITED STATES PATENT OFFICE.

DELBERT J. BRANNING, OF HAWLEY, PENNSYLVANIA.

DESIGN FOR A SHADE FOR AN ARTIFICIAL LIGHT AND LENS FOR AN AUTOMOBILE-HEADLIGHT.

52,631.

Specification for Design.

Patented Nov. 12, 1918.

Application filed January 19, 1918. Serial No. 212,844. Term of patent 14 years.

To all whom it may concern:

Be it known that I, DELBERT J. BRANNING, a citizen of the United States of America, residing at Hawley, in the county of Wayne and State of Pennsylvania, have invented a new, original, and ornamental Design for a Shade for an Artificial Light and Lens for an Automobile-Headlight, of which the following is a specification, reference being had to the accompanying drawing, forming part thereof.

The figure is a plan view showing my new design for a shade for an artificial light and lens for an automobile head light.

I claim:

The ornamental design for a shade for an artificial light and lens for an automobile headlight, as shown.

DELBERT J. BRANNING.
